DESULFURIZATION OF OLEFINIC NAPHTHA

John F. Deters, Valparaiso, Arthur P. Lien, Hammond, and Harold Shalit, East Chicago, Ind., assignors to Standard Oil Company, Chicago, Ill., a corporation of Indiana

No Drawing. Application November 29, 1949,
Serial No. 130,068

4 Claims. (Cl. 196—24)

1

This invention relates to an improved method of desulfurizing highly olefinic naphthas and it pertains more particularly to the desulfurization of coke still naphtha by extraction with dimethyl formamide containing less than 25 per cent of water, the extract being hydrodesulfurized for blending with the raffinate.

An object of the invention is to provide an improved method and means for removing sulfur compounds from highly olefinic naphthas without materially altering the olefin to paraffin ratios and without suffering large treating losses. A particular object is to desulfurize a naphtha in which the olefinic content substantially equals or exceeds the paraffinic content, an outstanding example of such naphtha being coke still naphtha. A further object of the invention is to convert a high sulfur olefinic naphtha into low sulfur olefinic gasoline of a high anti-knock value with minimum treating losses and with a minimum amount of olefins subjected to hydrofining when that process is employed for converting sulfur compounds to H_2S for facilitating their removal from extract material.

Dimethyl formamide is known to be useful in the extraction of hydrocarbon oils (U. S. 2,166,140) and when applied to heavy oils, it may contain water throughout a wide operating range (U. S. 2,183,852). In our invention, the dimethyl formamide is employed for extracting a particular type of stock, namely a high sulfur olefinic naphtha and it performs a function radically different from that which it performed in prior processes. We have discovered that when dimethyl formamide is employed as an extractant for high sulfur olefinic naphtha, it not only effects separation between aromatic and paraffinic hydrocarbons, but it serves the additional function of concentrating the sulfur in the extract phase while leaving the bulk of the olefins in the raffinate phase. This remarkable and unexpected property of dimethyl formamide makes it possible to concentrate sulfur from a high sulfur olefinic naphtha and the relatively small volume of extract contains only a minor amount of the olefins. The extract can then be hydrodesulfurized in the absence of raffinate and the hydrodesulfurized extract blended with the raffinate to produce a remarkably high yield of stable olefinic gasoline of high octane number.

The invention is applicable to high sulfur olefinic naphthas generally, i. e. to naphthas in which the olefin to paraffin ratio is in the range of about 3:1 to 1:3 and is particularly advantageous for charging stocks in which the olefinic

content exceeds the paraffinic content. By "high sulfur," we mean a sulfur content which is at least about .25 per cent and which is usually in the range of about .5 to 1 per cent or more. By "naphtha," we mean a normally liquid hydrocarbon fraction boiling below 450° F. and usually boiling almost entirely within the range of 100° to 400° F. An outstanding example of a high sulfur olefinic naphtha is the naphtha produced by the coking of high sulfur reduced crude in any known manner such, for example, as by continuously introducing heated charging stock into a coke drum at about atmospheric pressure to 50 pounds per square inch at a temperature in the range of about 850 to 950° F., and continuing the operation until coke solidifies in the drum, the vaporous products from the drum being fractionated into a coke still naphtha fraction and one or more heavier fractions. While the invention may be applicable to high sulfur olefinic naphthas produced by thermal cracking or by catalytic cracking, its outstanding advantage is in the refining of coke still naphtha because this particular high sulfur olefinic naphtha is the most difficult of all to desulfurize or otherwise refine by conventional methods.

Coke still naphtha has an olefin to paraffin ratio of approximately 2:1, and contains from about .25 to 4 per cent sulfur by weight, a representative stream containing for example about 1 per cent sulfur. The bromine number of the olefinic components of a representative coke still naphtha may be about 70 to 85 but there is a bromine absorption due to sulfur corresponding to about 5 bromine numbers per weight per cent sulfur. A correlation of bromine numbers and sulfur content in original charge, raffinate and extract, respectively, can thus be employed to determine the extent to which olefins are selectively removed from paraffins in an extraction process.

Our extractant is a di-aliphatic formamide, such for example as dimethyl formamide, methyl ethyl formamide, di-ethyl formamide, etc. Dimethyl formamide is a preferred solvent, and although it boils at 153° C., which is within the boiling range of the olefinic naphtha, it may be readily separated from raffinate and extract by simple water washing and then separated from water by simple distillation since it does not form azeotropes or constant boiling mixtures with water. Such a solvent is heat stable, but will not polymerize or form tars when heated, is non-corrosive and is completely miscible with water. In addition, its density of 0.953 gm./ml. is such that it is easily separated from petroleum stocks.

For optimum results, the dimethyl formamide should contain a small amount of water which should be less than 25 per cent and usually in the range of about 1 to 10 per cent, or approximately 2 per cent when the solvent to oil ratio is of the order of 1:1, larger water contents being permissible with higher solvent to oil ratios. The water is most effectively utilized when introduced into the extract portion of a countercurrent extraction system. Thus, when a countercurrent tower extractor is employed, a small amount of the water is most effectively utilized when introduced into the extract phase near the point of charging stock inlet or between this point and the bottom of the tower. The invention is not limited to tower type extraction, however, and the extraction may be effected batchwise, in a multiple batch system, in a countercurrent batch system, or by any other extraction method known to those skilled in the art.

The extraction can best be carried out with a solvent to charging stock volume ratio in the range of 3:1 to 3:1, the preferred range being about 5:1 to 1:1. The extraction may be effected at ordinary room temperature or within the range of about 0° C. to 50° C. The pressure should be such as to keep all material in liquid phase.

As a specific example of the invention, the following data were obtained when a coke still naphtha (produced by the coking of West Texas gas oil) of about 81 bromine number and containing about .9 weight per cent sulfur was extracted at room temperature with dimethyl formamide containing 2 per cent by volume of water, and employing a solvent to oil ratio of 1:1, the extraction having been effected in the countercurrent column packed with glass beads.

	Vol. per- cent	Weight percent S	Br. No.	Cor- rected Br. No.	Ratio: Weight Percent S/Corr. Br. No.
Charge	100	.9	81	77	.012
Raffinate	60	.15	72	71	.002
Extract	40	1.85	87	78	.024

From the above data it will be noted that the dimethyl formamide was remarkably effective in concentrating the sulfur in the extract phase without preferentially extracting olefins to any appreciable extent. The bromine number of the extract when corrected for its sulfur content was of substantially the same order of magnitude as the original charging stock. The sulfur to olefin ratio in the extract (on the basis of corrected bromine number) was twelve times that of the raffinate, thus indicating the remarkable effectiveness of the solvent for concentrating sulfur in the extract without appreciably concentrating olefins so that when the extract is subjected to hydrodesulfurization, only a minor proportion of the olefins present in the original charging stock will be subjected to hydrogenation conditions which might lead to their saturation.

In another example of our invention, the following data were obtained when a coke still naphtha (from the coking of mixed Mid-Continent and West Texas gas oils) of about .4 weight per cent sulfur was extracted at room temperature with dimethyl formamide containing the indicated amounts of water with countercurrent extraction procedure employing a solvent to oil ratio in each case of about 8:1:

	Vol. Percent	Weight Percent S	Br. No.	Cor- rected Br. No.	Ratio: Weight Percent S/Corr. Br. No.
Charge	100	.4	50	48	.008
No water:					
Raffinate	43	.03	47	47	.0006
Extract	57	.61	55	52	.012
3% water in solvent:					
Raffinate	77	.10	51	50	.002
Extract	23	1.09	52	47	.023
5% water in solvent:					
Raffinate	83	.14	48	47	.003
Extract	17	1.22	51	45	.027

The above data indicate that with no water, the raffinate is of remarkably low sulfur content, but produced at a yield of less than 50 volume per cent. With 3 per cent by volume of water in the solvent, the raffinate yield is almost doubled and its sulfur content is only .10 weight per cent. With 5 weight per cent of water in the solvent, the raffinate yield is still higher, but its sulfur content has increased to .14 weight per cent. Thus it appears to be markedly advantageous to employ a water content of about 1 per cent to 5 per cent when the water is employed with introduced solvent and when the solvent to oil ratio is approximately 0.8:1.

The sulfur to olefin ratio (as indicated by weight per cent sulfur divided by corrected bromine number) shows the remarkable extent to which sulfur is concentrated in the extract to the relative exclusion of olefins. With no water, the extract ratio is about 20 times the raffinate ratio. With 2 per cent water, the extract ratio is about 11 times the raffinate ratio. With 5 per cent water, the extract ratio is about 9 times the raffinate ratio. The above figures clearly show the remarkable effectiveness of dimethyl formamide for desulfurizing a high sulfur olefinic naphtha without concentrating olefins in the extract phase. The corrected bromine numbers themselves show that the extract phase does not contain an appreciably higher concentration of olefins than were present in the original charging stock and that with water in the solvent, the extract actually contained a lower proportion of olefins than was contained in the original charging stock.

It should be understood that increased concentrations of water may be used in either of the above examples in order to obtain higher raffinate yields, but in so doing, the extent of desulfurization will be diminished.

When dimethyl formamide is employed as the extractant, separation of the solvent from extract and raffinate is effected by simple water washing and the solvent can then be separated from the water by simple distillation. With sufficiently high boiling di-alkyl formamides, the separation of solvent from raffinate and extract may be effected by simple distillation.

The sulfur content of the raffinates produced by our invention is sufficiently low so that they may be blended in finished gasoline to meet stringent sulfur specifications. The extract which only constitutes a small fraction of the original charging stock, but which contains most of the sulfur compounds, may be hydrodesulfurized by any known process, such, for example, as hydroforming, hydrofining, autofining, etc. The catalysts employed for this step may be an eighth group metal or metal sulfide as described in U. S. 2,273,297, but it is preferably a supported sixth

group metal compound, such as chromium or molybdenum oxide on alumina as employed in hydroforming (note U. S. 2,388,536) or supported cobalt molybdate as used in hydrofining (note Ind. Eng. Chem., vol. 35, pages 1160 to 1167), or tungsten sulfide-nickel sulfide as described in the paper presented by Eagle and Rudy entitled "Application of Cyclic Adsorption Process to Desulfurization of Cracked Naphtha" before the American Chemical Society in September 1949. Autofining is similar to hydrofining except that the hydrogen is supplied by naphthenes added to the charging stock. Since these hydrodesulfurization processes are well-known to those skilled in the art (product yields and product qualities, both alone and blended with initially separated components being likewise known, as described for example in the Eagle and Rudy paper), it is unnecessary to describe the hydrodesulfurization or the yields and properties of finished motor fuel in further detail.

Our invention provides an enormously simpler and less expensive method of treating a high sulfur olefinic naphtha for obtaining a relatively small amount of extract of high sulfur and low olefin content than was heretofore known to the art. Since only the extract requires hydrodesulfurization and the raffinate (which contains most of the olefins) is not subjected to hydrodesulfurization, we minimize hydrodesulfurization expense and avoid saturation of any olefins separated as raffinate. We thus not only obtain higher yields of a finished product blend, but we obtain a finished product blend of remarkably high octane number and at a relatively low cost.

While our invention has been described with respect to specific operating examples, it should be understood that alternative operating conditions and modifications will be apparent to those skilled in the art. Other di-alkyl formamides which are substantially equivalent in extraction properties to dimethyl formamide may be employed instead of dimethyl formamide itself.

We claim:

1. The method of obtaining a low sulfur olefinic gasoline of high anti-knock value from a high sulfur olefinic naphtha which comprises extracting a naphtha having an olefin to paraffin

ratio in the range of 3:1 to 1:3 and containing more than .25 per cent sulfur with a di-alkyl formamide under conditions to form an extract phase containing most of the sulfur and a raffinate phase containing most of the olefins, separately removing solvent from each of said phases, hydrodesulfurizing the solvent-free extract phase to eliminate sulfur therefrom and blending the hydrodesulfurized extract with the solvent-free raffinate.

2. The method of claim 1 which includes the step of employing with the di-alkyl formamide an amount of water in the range of about 1 to 5 per cent by volume based on total solvent.

3. The method of claim 2 wherein the di-alkyl formamide is dimethyl formamide.

4. The method of desulfurizing a high sulfur coke still naphtha having an end point below 450° F. and having an olefinic content which is higher than its paraffinic content, the sulfur content of said naphtha being in the range of .25 to 4 percent, which method comprises extracting said high sulfur coke still naphtha with dimethyl formamide to produce raffinate and extract phases, employing an amount of water in the range of about 1 to 5 percent by volume based on total solvent at least in the extract phase to increase raffinate yield without substantially decreasing desulfurization, separating solvent from the resulting raffinate and extract phases, hydrodesulfurizing the solvent-free extract in the absence of olefin separated in the raffinate phase and blending naphtha-boiling-range products of the hydrodesulfurizing step with the solvent-free raffinate to obtain a desulfurized naphtha product rich in olefins.
